(57) **CLAIM**

The ornamental design for a case for a handtool, especially for office work, as shown.

DESCRIPTION

FIG. 1 is a first perspective view from above and from one side of a first variant;

FIG. 2 is a second perspective view from above and from the other side of the first variant;

FIG. 3 is a perspective view of the first variant in open state;

FIG. 4 is a front elevational view of the first variant;

FIG. 5 is a rear elevational view of the first variant;

FIG. 6 is a cross-sectional view taken along the line 6—6 of FIG. 1;

FIG. 7 is a right side elevational view of the first variant;

FIG. 8 is a left side elevational view of the first variant;

FIG. 9 is a cross-sectional view taken along the line 9—9 of FIG. 1;

FIG. 10 is a top plan view of the first variant;

FIG. 11 is a bottom plan view;

FIG. 12 is a first perspective view from above and from one side of a second variant;

FIG. 13 is a second perspective view from above and from the other side of the second variant;

FIG. 14 is a perspective view of the second variant in open state;

FIG. 15 is a front elevational view of the second variant;

FIG. 16 is a rear elevational view of the second variant;

FIG. 17 is a cross-sectional view taken along line 17—17 of FIG. 12;

FIG. 18 is a right side elevational view of the second variant;

FIG. 19 is a left side elevational view of the second variant;

FIG. 20 is a cross-sectional view taken along line 20—20 of FIG. 12;

FIG. 21 is a top plan view of the second variant; and,

FIG. 22 is a bottom plan view.
